UNITED STATES PATENT OFFICE.

MARTIN V. HAMMACK, OF RALEIGH, NORTH CAROLINA, ASSIGNOR OF ONE-HALF TO
ALBERT L. CGX AND ONE-HALF TO JOSEPH S. HAMMACK, BOTH OF RALEIGH, NORTH
CAROLINA.

TROUSERS APPLIANCE.

1,165,093.

Specification of Letters Patent.

Patented Dec. 21, 1915.

Application filed February 1, 1915. Serial No. 5,543.

To all whom it may concern:

Be it known that I, MARTIN V. HAMMACK, a citizen of the United States, residing at Raleigh, in the county of Wake and State of North Carolina, have invented certain new and useful Improvements in Trousers Appliances, of which the following is a specification.

My invention relates to improvements in trousers appliances, this invention being an improvement upon the invention covered by patent granted to me July 21, 1914, No. 1,104,188, the main object being to improve the construction of the appliance covered by said patent and overcome its defects and provide a more efficient and practical appliance for the purpose intended.

Another object of my invention is the provision of a trousers appliance which will permit of a unitary structure providing an appliance to fit in both legs of the trousers and thus produce in one structure a device which will be applied to both of the legs of the trousers.

With these objects in view, my invention consists of a trousers appliance embodying novel features of construction, combination and arrangement of parts for service, substantially as shown, described and claimed herein.

Figure 1 represents a side elevation of my trousers appliance. Fig. 2 represents an edge view showing the double or twin construction of my appliance. Fig. 3 represents a sectional view of the tubular member of my appliance. Fig. 4 represents a sectional view through one of the arms of the adjusting member, and Fig. 5 represents a view taken on the line 5—5 of Fig. 2.

Referring by letters to the drawings, in which similar letters denote like parts, in all the figures of the drawings, the letter A designates the main supporting member of my appliance which is tubular in construction and made in two sections, connected by a pin B, which construction permits the member to be taken apart when desired and to the lower end of the tubular member is connected the three-way coupling C, in the horizontal portion of which is screwed the pair of guide tubes D, and from said tubes leads the loop E for suspending the hanger or appliance. To the upper end of said tubular member is connected the cross-head

F comprising a pair of arms formed at their end with guides or kerfs G, and a vertical tubular threaded stem H. Mounted in said stem is the adjusting screw J, having at its upper end the adjusting handle portion K and having mounted adjacent said handle portion the collar L, to which is pivoted at M, the upper ends of the pair of spreaders N, which are guided in the kerfs G, and have connected at their outer ends O, the upper end of the trousers engaging wires P, whose lower ends are secured at Q to the pair of laterally adjustable arms R, fitting in the guide tubes D, and being adjustable to suit the width of the bottom of the trousers.

The appliances are connected in pairs by means of the plate S, having a turned or doubled portion S', and the flanged plate T, guided in said plate S, and the plates are secured together by means of the hand-screw U, which connects the plate as shown in Fig. 2, thus securing together the two parts of the appliance.

The manner of using my appliance is exactly the same as in my former patent, the appliance being placed in the trousers legs and the spreaders adjusted to cause the wires to bear against the trousers to effect the stretching and creasing of the trousers.

It will be understood that a separate appliance may be used for each trousers leg, but I prefer to use the appliances embodying the pair or twin construction, as this enables the appliance to be fitted in each leg of the trousers and to hold the trousers in proper hanging position as well as to insure the proper creasing and preserving of the shape of the trousers.

It will be noted that the pair of stretchers can be collapsed and brought together to permit the device to occupy a small amount of space, or they may be extended or moved apart by means of the nut U', on screw U, which permits one section to be moved by means of the slot U² and clamped or secured in the desired adjustment.

I claim:

A trousers appliance, consisting of two similar stretching devices, each comprising a supporting member, a pair of sleeves connected to the lower end of each supporting member, a pair of arms adjustable in said sleeves, an adjustable cross head connected

to the upper end of each supporting member, an adjusting screw mounted in each of said heads, a pair of spreaders having their upper ends connected to each of said screws and guided in the cross heads, trousers engaging wires connected to the lower ends of said spreaders, said wires having their lower ends connected to the adjustable arms, plates connected to the said cross heads in twin

relation, and a screw for retaining said 10 plates in connected relation.

In testimony whereof I affix my signature in presence of two witnesses.

MARTIN V. HAMMACK.

Witnesses:

O. G. WRENN,
CARY K. DURFEW.
